NON-RAVELING SPREADING MOP CONSTRUCTION

Teron V. Moss, Shaker Heights, Ohio

Application July 24, 1953, Serial No. 370,199

9 Claims. (Cl. 15—229)

This invention relates as indicated to a novel mop construction and more particularly to a mop constructed and arranged for maximum efficiency in mopping floors dry and the like.

In the past mops have generally comprised bundles of yarn or the like secured to an appropriate holder, ordinarily on a long handle. In use the individual yarns or strands tend to become tangled quickly, to unravel at their ends, and eventually to become matted together. Such mops are very inefficient in their primary function of absorbing the maximum amount of water possible from the surface of the floor and they tend to disintegrate rapidly once the plies of the yarn become untwisted.

It is accordingly a principal object of my invention to provide a mop construction in which the individual strands or cords are oriented in a particular manner for maximum floor coverage and efficiency of water absorption and also restrained against undue untwisting in use.

A further object is to provide such mop construction in which the individual cords will not readily become confused and tangled.

Another object is to provide a mop in which the extreme ends of the strands will be particularly effective as water absorbing means.

Still another object is to provide means effective to prevent undue raveling and whipping of the ends of the cords or strands.

Other objects of this invention will appear as the description proceeds.

To the accomplishment of the foregoing and related ends, said invention then comprises the features herein-after fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 represents a general plan view of my new mop, it being understood that the cords or yarns extend similarly to either side of the fabric band securing the same together;

Figs. 2 and 3 are views similar to Fig. 1 on a reduced scale and showing a modified arrangement or modified designs or stitching or the like interconnecting the individual strands in desired manner;

Fig. 4 is an edgewise view of the mop assembly of Fig. 1;

Fig. 5 is an enlarged fragmentary view of several adjacent mop strands illustrating the manner in which they are secured together in spaced relation;

Fig. 6 is a diagrammatic showing of a form of lock stitch which may suitably be employed for the purpose of thus interconnecting the mop strands; and

Figs. 7-11 inclusive illustrate further modifications of my new mop construction.

Referring now more particularly to said drawing, the

2

mop of my invention may conveniently be produced by unreeling appropriate stranded material such as long fiber bleached hemp yarn or cord, for example, from a supply thereof and securing wide fabric bands such as 1 thereabout at spaced intervals by means of stitching 2. The stranded material may then be severed midway between such fabric bands 1 to provide the mop elements as generally illustrated in Figs. 1-4 inclusive comprising such central fabric bands 1 with the bundle of stranded material several layers thick retained therein. Such stranded material 3 may be fanned out in accordance with my invention until the extreme end portions thereof are only one layer thick and the cords or yarns are spaced one from the next as shown in Fig. 5. Such cords or yarns are then stitched together in such spaced relationship preferably with nylon thread 4, utilizing a lock stitch such as that illustrated in Fig. 6, for example, so that if the stitching should later be broken in use it will not unravel to release adjacent cords. Figs. 2 and 3 show similar arrangements wherein additional stitching 5, 6 and 7 may be utilized, if desired. Such stitching 4 may be doubled by also stitching from the other side of the mop, but usually a single pass of the sewing machine will suffice.

It will be appreciated that the fabric band 1 securing the bunched mop strands together is more or less conventional and the particular means for thus securing the mop material in a generally flattened bunched condition does not constitute a part of the present invention.

The stitching 4 not only serves to maintain the oriented arrangement of the individual cords or yarns, but also prevents raveling of the end portions. Such stitching may, for example, be located approximately 2 inches from the ends of the cords or yarns when the latter extend approximately 13 inches from the fabric band 1. By employing nylon thread for such stitching, the likelihood of snapping the same should the mop be caught upon some obstruction is much reduced. The stitching 5, when employed, assists in maintaining the desired relationship of the cords, such stitching being located approximately midway between stitching 4 and fabric band 1. The additional optional stitching 6 and 7 (Fig. 3) arranged in arcs or scallops in from the sides of the mop further assist in maintaining the mop material in the illustrated fan-shaped relationship.

When the user is mopping the floor, and more particularly dry mopping the same, the mop will be swung so as to cause the yarns or cords to spread out in the manner generally indicated in Fig. 1, although of course when the mop is dipped in a bucket or wrung out for example, the end portions will fold together. The Fig. 2 and Fig. 3 modifications tend to maintain the fan-shaped relationship of the cords or yarns to a greater degree and further minimize tangling of the yarns.

My novel mop construction renders feasible the employment of twisted long fiber moisture absorbing material such as bleached hemp yarn which is strong as well as highly water absorbent, since the stitching prevents raveling back too far from the ends. Moreover, the partially unraveled end portions of the twisted cords are particularly water absorbent and when fanned out as they are in accordance with my invention, each of such cord ends is rendered effective for this purpose since each will contact the surface being mopped. I further contemplate the inclusion of a relatively small percentage of braided nylon cord, or cord comprising a mixture of nylon and cotton, or nylon and hemp to afford a supplemental abrasive action. Such relatively expensive materials may be included in my new mop and their inclusion justified for the reason that they will contact the surface being mopped. In the ordinary mop where the strands are considerably bunched together even toward their outer

ends, the inclusion of a small number of special cords therein would ordinarily be without much effect inasmuch as a number of them would be enclosed within the mop structure and seldom, if ever, contact the surface being mopped.

My new mop construction may afford a spread of two or more times the width of the mop at the central retaining band 1 when such mop is thrown out on the floor, and each strand is allowed sufficient freedom to cover a maximum of floor area. Since the outer surface of each strand is substantially unobstructed by adjacent strands in the outer end portions of the mop, it is afforded the maximum opportunity to absorb water. Maximum floor coverage and maximum effectiveness are thus combined. As best shown in Fig. 5, the individual yarns are separate and spaced apart adjacent their outer ends but connected to each other by a chain of stitching 4.

The mop swab of Fig. 7 is generally similar to that of Fig. 1 except that additional lines of stitching 8 and 9 may be included. Fig. 8 shows scalloped stitching 10 and 11 and Fig. 10 comparable crossed stitching 12 and 13. It is usually desired that stitching corresponding generally to stitching 4 be employed in conjunction therewith, however, properly to control the end portions of the yarns or cords. Thus in Fig. 11 there is shown a combination of crossed stitching 14 and 15 and transverse stitching 16 and 17, and in Fig. 9 crossed stitching 18 and 19 and transverse stitching 20 and 21.

The stitching 4 or equivalent is far enough back from the ends of the yarn or cord 3 to permit this portion to be open to pick up water but yet incapable of untwisting far enough to lint off onto the floor. As previously indicated, all stitching, and particularly that near the ends of the yarns, may desirably be of nylon. A small percentage of braided, sewed, twisted or knitted nylon cord may be included for its abrasive action with the more absorbent twisted mop yarn or cord 3.

My new mop is thus inexpensive of construction, permits the employment of preferred materials, and enables the mop strands to spread out over a maximum area with maximum absorbing effect, yet without tangling and with all of the strands maintained in their proper respective relationship. While shown and described as forming two swab portions divided by the central fabric band or equivalent securing means it will be apparent that but a single such swab portion of fan shape may be utilized if desired. It will be appreciated that certain other synthetic plastic strands commercially available other than nylon, such as Orlon and Dacron, may be utilized in forming a small proportion of the mop strands for their abrasive effect, but nylon is ordinarily preferred.

Other modes of applying the principle of the invention may be employed, change being made as regards the details described, provided the features stated in any of the following claims or the equivalent of such be employed.

I therefore particularly point out and distinctly claim as my invention:

1. A mop swab comprising a bundle of a plurality of layers of twisted stranded cords, said bundle being secured together in generally flattened form midway of its ends by a wide fabric band encircling the same and stitched thereto, the individual cords of said mop swab being fanned out to form but a single layer in their end portions with the latter appreciably spaced apart, and a line of nylon lock stitching interconnecting all such cords in a region spaced a short distance inwardly from the ends of said cords.

2. A mop construction as defined in claim 1 having an additional similar line of nylon lock stitching inter-

connecting all said cords in a region intermediate said first stitching and said encircling fabric band.

3. A mop construction as defined in claim 2 having additional generally arcuate lines of nylon lock stitching extending inwardly from the respective sides of the swab to the longitudinal center line thereof with each line of stitching extending from said encircling fabric band to the ends of the outermost cords.

4. In a mop construction comprising a bundle of absorbent strands secured together in a plurality of layers intermediate their ends, means flexibly interconnecting the outer end portions of the individual strands of said bundle with the end portions of said strands fanned out into a single layer and spaced each from the other.

5. In a mop construction comprising a bundle of absorbent strands secured together in a plurality of layers intermediate their ends, means flexibly interconnecting the outer end portions of the individual strands of said bundle with the end portions of said strands fanned out into a single layer and spaced each from the other, said bundle including a small proportion of strands composed of nylon and cotton.

6. In a mop construction comprising a bundle of absorbent strands secured together in a plurality of layers intermediate their ends, means flexibly interconnecting the outer end portions of the individual strands of said bundle with the end portions of said strands fanned out into a single layer and spaced each from the other, said bundle including a small proportion of less absorbent but more abrasive synthetic plastic strands.

7. In a mop construction comprising a bundle of absorbent strands secured together in a plurality of layers in a region adapted to be secured to a handle, means flexibly interconnecting the outer end portions of the individual strands of said bundle with the end portions of said strands fanned out into a single layer and spaced each from the other.

8. A mop swab comprising a bundle of absorbent strands, means securing said strands together in a plurality of layers in an area remote from a free end of said bundle, and flexible means intermediate said securing means and said free end of said bundle interconnecting the individual strands of said bundle with said strands fanned out into a single layer and spaced each from the other, the free end of said bundle thus comprising a single layer of free strands.

9. A mop swab comprising a bundle of a plurality of layers of twisted stranded cord, said bundle being secured together in a generally flattened form in an area remote from one end of said bundle by a wide fabric band encircling the same and stitched thereto, the individual cords of said mop swab being fanned out to form a single layer with said strands appreciably spaced apart in an area a short distance toward said fabric band from said end, and a line of nylon lock stitching interconnecting all said cords in said area.
